UNITED STATES PATENT OFFICE.

EZRA H. SAWYER, OF VINELAND, NEW JERSEY, ASSIGNOR TO BURT MACHINE COMPANY, A CORPORATION OF DELAWARE.

MACHINE FOR APPLYING IDENTIFYING-MARKS TO CANS.

No. 867,928.

Specification of Letters Patent.

Patented Oct. 8, 1907.

Application filed March 7, 1907. Serial No. 361,048.

To all whom it may concern:

Be it known that I, EZRA H. SAWYER, of Vineland, in the county of Cumberland and State of New Jersey, have invented certain Improvements in Machines for Applying Identification-Marks to Cans, of which the following is a specification.

This invention relates to means whereby the name, or initials of a packer or dealer in canned goods, or some arbitrarily selected identifying mark is imprinted on the body of cans or the labels covering them, as will hereinafter fully appear.

The said invention may be incorporated in a machine which has no office other than that of carrying the cans to and from the marking appliances, in which case should a liquid marking medium be used, and it is found desirable, heat is applied to the can to dry the impression.

Another application of the invention consists in its incorporation in a labeling machine where the impression is made on the can body, or on the label covering the same. Should the impression be made on the can body and a label immediately wrapped over it, the impression would be transferred to the inner surface of the label, and in that case the inverted marks would identify the labels should the same be stripped from the cans and returned to the packer or dealer for redemption.

In the further description of the said invention which follows, reference is made to the accompanying drawings forming a part hereof, and in which,—

Figure 1 is a partly sectional side elevation of certain parts of a machine through which cans are conveyed and an identifying mark applied to them during their passage, without respect to any labeling operation. Fig. 2 is an enlarged partly sectional view of certain parts of the machine as they appear in Fig. 1. Fig. 3 is a view of Fig. 2 looking in the direction indicated by the arrow in that figure. Fig. 4 is a side view of the entrance end of a can labeling machine in which the marking devices are incorporated, and illustrating the construction and arrangement employed when the cans are marked before receiving the label. Fig. 5 is a view similar to Fig. 4 except that the discharge end of the machine is shown, the identifying mark being applied to the outside of the wrapper or label instead of to the can body.

Referring now to Figs. 1, 2 and 3 of the drawing, 1 represents the bed of the machine, and 2 and 3 respectively, the feed or entrance, and the delivery runway. 5, 5 denote cans two of which are shown in Figs. 1 and 4, and one in Fig. 5. 7, 7 are stands arranged in pairs on the bed 1, the upper ends of which serve as bearings for the shafts *a* to which are secured the pulleys 9. 10 is an endless conveyer belt carried by

the pulleys 9, the lower lay of which serves to transfer the cans along the bed 1 from the entrance to the delivery runway. The pair of stands 7 next to the entrance runway is provided with two arms 12 but only one of these arms appears, the other being behind. The ends of these arms extend over the entrance runway 2 and are slotted and within the slots is placed a shaft *b* to which is fastened a marking wheel 13. A partly sectional side view of the marking wheel on an enlarged scale, is shown in Fig. 2.

Referring to Fig. 3 it will be seen that the marking wheel 13 has one flange *c* integral with the body, and that the body is grooved to receive type blocks one only of which blocks is represented and denoted by *d* in Figs. 2 and 3. The marking wheel shaft *b* has a pulley 14 which is driven from the adjacent shaft *a* 70 through the medium of a pulley not shown, and the belt *e*. The cans in passing from the entrance runway to the bed of the machine, pass under the marking wheel and receive an impression therefrom.

In order that the type blocks may be inked, there is placed over the marking wheel an inking roller 15 provided with a felt covering *f* (see Fig. 2) and above the felt covered roller is an ink distributing roller 17. The shafts of the marking wheel and the ink applying and distributing rollers described, are journaled in 80 bars *g*, and the shaft *h* of the felt coated wheel is threaded at its ends and fitted with nuts *j* which serve to prevent dislocation of the inking apparatus. The ends of the shaft *k* of the ink-distributing roller rest loosely in the ends of arms 19 which are adapted 85 to swing on the shaft *a*, consequently the inking roller with its attachment is susceptible of being lifted to the extent of the length of the slot in the stationary arms 12. Within an aperture *m* in the bed 1 is placed a heating burner 20 over which the cans pass when 90 traversing the bed 1, and the position of the said burner is such that the printed mark will be exposed to the flame and be dried by heat.

The application of the invention to a labeling machine so that the identifying mark will be covered 95 by a label, is shown in Fig. 4, and it will be seen that the machine differs from the one just described only in that the heating and drying burner is omitted, and that a stack of labels denoted by 21 is placed in the path of the cans as they traverse the bed 1. In case 100 the impression on the cans is to be transferred to the inner surface of the labels, it is only necessary to select an ink of the proper fluidity, when the result of having labels marked in reverse for redemption as before stated, is effected.

The arrangement of the invention in order that the impression will be made on the outside of the labels is shown in Fig. 5 in which the imprinting appliances

are situated between the entrance and the delivery runways, or in such position that the impression is made on the labels, after the same are applied to the cans.

5 Referring to Figs. 1 and 4 it will be seen that the marking wheel 13 being situated over the inclined runway which delivers the cans to the bed of the machine by gravity, also serves to separate or space the cans on the bed, an important feature if the cans 10 are to be subsequently labeled, or if a mark printed directly on the can body has to be dried by a burner, consequently the usual spacing devices are not required. With the construction shown in Fig. 5 the 15 ordinary spacing devices are required, as the marking is performed while the cans are on the bed, and after the labels are applied to the cans. In both constructions, however, the marking wheel is free to rise and fall thus adapting the apparatus to give a uni-

form impression should the bodies of the cans be distorted in shape by indentations, or should the cans 20 vary slightly in diameter.

I claim as my invention:

1. In a machine for applying identifying marks to cans, a bed, a conveyer belt to carry the cans along the bed, and an inclined runway to deliver cans to the conveyer belt, combined with a marking device placed over the inclined runway under which the cans pass and from which the cans receive an impression, substantially as specified. 25

2. In a machine for applying identifying marks to cans, a bed and a conveyer belt to carry the cans along the bed, combined with a stand erect on the bed, a swinging arm supported from the stand, bars pendent from the swinging arm, and a rotary marking wheel supported by the said pendent bars adapted to bear on the cans as the same pass through the machine, substantially as specified. 30

EZRA H. SAWYER.
